REAR SIGHT

Thomas J. Heavey, United States Army,
Fort Riley, Kans.

Application September 11, 1934, Serial No. 743,539

6 Claims. (Cl. 33—55)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a rear sight for guns and more particularly it has reference to a sight which is to be employed in pointing a gun at rapidly moving aerial targets.

10 The purpose of the invention is to provide a strong, simple and compact rear sight having a readily adjustable slide carrying sighting rings. A further object of the invention is to provide a novel mounting of the sight to enable it to be quickly swung about a longitudinally disposed pin 15 which is hollow so as to also serve as a sighting aperture.

15 With the foregoing and other objects in view, the invention resides in the novel arrangement and combination of parts and in the details of 20 construction hereinafter described and claimed, it being understood that changes in the precise embodiment of the invention herein disclosed may be made within the scope of what is claimed without departing from the spirit of the invention.

25 A practical embodiment of the invention is illustrated in the accompanying drawing, wherein:

Fig. 1 is a view in side elevation of the improved 30 rear sight.

Fig. 2 is a view in rear elevation of Fig. 1.

Fig. 3 is a view in rear elevation with the sight in horizontal position and fully extended.

Fig. 4 is a sectional view on the line 4—4 of 35 Fig. 3.

Fig. 5 is a sectional view on the line 5—5 of Fig. 2 with the slide removed.

Fig. 6 is a detail view of the leaf.

Fig. 7 is a detail view of the bar.

40 Fig. 8 is a detail view of the slide.

Fig. 9 is a detail view of the clutch plate.

Referring to the drawing by characters of reference there is shown a base 5 having spaced apertured ears 6—6 for receiving a horizontally disposed hinge pin 7 on which is mounted a leaf 8. This construction is similar to that of a typical rear sight, the leaf being foldable against the base or raised to a vertical position where it is held by the conventional spring 9. In the present showing convenience has dictated the formation of the leaf 8 by modifying an existing rear sight.

50 For the purpose in view, the leaf 8 is of small length and has a rather large aperture 10 and a number of small holes 11. An annular clutch

plate 12 with a relatively large aperture 13 adapted to be in alignment with the aperture 10 is attached to the upper or rear face of the leaf by means of screws 14 passing through the holes 11 and threadedly secured to the plate. The outer or exposed face of the plate 12 is formed with a large number of radially disposed teeth 15.

5 This invention relates to a rear sight for guns and more particularly it has reference to a sight which is to be employed in pointing a gun at rapidly moving aerial targets.

A bar comprising spaced rails 16—16 includes on its lower end a plate 17 which is provided with radially disposed teeth 18 adapted to mesh with the teeth 15 of the plate 12. The plate 17 is formed with an aperture 19 adapted to be in alignment with the apertures 10 and 13. The bar is pivotally mounted on a longitudinally disposed hollow pin 20 passing through the apertures 19, 13 and 10. The pin 20 has a head 21 on one end engaging the plate 17 and is held against removal by a nut 22 threaded on the opposite end. A helical spring 23 surrounding the pin and confined between the plate 12 and the nut 22 normally holds the radial teeth 18 and 15 in engagement to maintain the bar in position of angular adjustment but yields when pressure is applied to the bar to swing it about the hollow pin 20.

25 The rails 16 of the bar are formed with grooves 24 for receiving a slide 25 having a large center opening 26 and having at its ends sighting rings 27 and 28. One of the sides of the slide 25 is formed with a series of recesses 29 adapted to be entered by a plunger 30 carried by the bar. The plunger is normally held against the slide by a spring 31 which is retained in place by a screw 32.

30 The ring 27, which is the inner ring when the slide is assembled to the bar, is inscribed on opposite sides with a pair of reference marks 33 and 34 respectively readable against scales 35 and 36 inscribed on the spaced rails 16 of the bar. The scale 35 is marked 0 to 80 and the scale 36 is marked from 80 to 160. These designations represent angular values in mils between the axis of bore and the line of sight passing through the front sight of the gun. The distance between the center of the rings 27 and 28 is equal 40 to 80 mils on the scales so that the reading of the reference mark 34 on the scale 36 indicates the angular displacement of the line of sight passing through the outer ring 28.

45 The sight is intended primarily for machine guns and is employed in pointing the gun at rapidly moving aerial targets. When the sight is not in use it is folded against the base 5 as indicated in dotted lines in Fig. 1. It is brought into operative vertical position as shown in full 50 55

lines in Fig. 1 by swinging it about the hinge pin 7.

The sight bar is swung to the right or to the left about its pivot 20 depending on the apparent course of the target relatively to the gun and where vertical corrections are to be considered in addition to lateral corrections the sight bar will be at an appropriate angle between the horizontal and the vertical. When the "angular lead" has been determined by the gunner or announced to him, he moves the slide until one or the other of the reference marks 33 or 34 are in register with the corresponding division of the scales 35 and 36 and then sights through the appropriate ring 27 or 28.

When lateral corrections to the line of sight are not required the sight bar is moved to the vertical position where the vertical correction is applied in the manner just explained. In the situation where the target is moving directly at the gun the line of sight is taken through the hollow pivot pin 20.

If the gun is also to be employed against ground targets, the usual sight scaled in terms of range will be used in addition to the present one, or the range will be interpreted in terms of quadrant elevation and read on the scales 35 and 36.

I claim:

1. In a rear sight, a base, a leaf pivotally mounted transversely of the base, an apertured plate attached to the base and having radially disposed teeth on its outer face, a bar having an apertured plate with radially disposed teeth adapted to engage the teeth on the plate of the leaf, a hollow pin passing through the apertured plates of the bar and the leaf, a nut on the pin, a spring surrounding the pin and confined between the nut and the leaf, a slide carried by the bar and having a pair of sighting rings spaced along its length, reference marks on opposite sides of the inner ring, means for holding the slide in position on the bar, a scale of low angular values on one side of the bar and a similar scale of higher values on the other side of the bar, said rings being spaced a distance coordinated with the length of said scales.

2. In a rear sight, a hollow pin serving as a sighting aperture, a bar pivotally mounted on

the pin for movement transversely of a line of sight and including spaced rails, a scale of low values on one rail, a scale of higher values on the other rail, a slide mounted for movement between the rails, a pair of sighting rings on the slide and spaced along its length a distance coordinated with the length of said scales, means for holding the slide in position on the bar, and reference marks on opposite sides of the inner ring and readable against the scales. 10

3. In a rear sight, a hollow pin serving as a sighting aperture, a bar pivotally mounted on the pin for movement transversely of a line of sight, a slide carried by the bar and having a pair of sighting rings spaced along its length, means for holding the slide in position on the bar and means indicating the displacement of the sighting rings from the axis of the hollow pin. 15

4. In a rear sight, a pivotally mounted bar, a scale of low values on the bar, a scale of higher values on the bar, a slide carried by the bar and having inner and outer sighting rings spaced along its length a distance equal to the length of the low value scale, and references on the inner ring of the slide readable against the respective 25 scales.

5. In a rear sight, a base, a leaf pivotally mounted transversely of the base and including an apertured plate having radially disposed teeth on its rear face, a sight bar having an apertured 30 plate with radially disposed teeth adapted to engage the teeth on the plate of the leaf, a hollow pin passing through the apertured plates of the bar and the leaf and serving as a sighting aperture, a nut on the pin and a spring surrounding 35 the pin and confined between the nut and the leaf.

6. In a rear sight, a base, a leaf pivotally mounted transversely of the base and including an apertured plate having radially disposed teeth on its rear face, a sight bar having an apertured 40 plate with radially disposed teeth adapted to engage the teeth on the plate of the leaf, a pin passing through the apertured plates of the bar and the leaf and extending longitudinally of the base whereby the sight bar may be swung transversely of the base, a nut on the pin and a spring surrounding the pin and confined between the nut and the leaf. 45

THOMAS J. HEAVEY.
